UNITED STATES PATENT OFFICE.

ELMER G. FIPPENGER, OF NEKOOSA, WISCONSIN.

BLOWER FOR SILOS.

Application filed February 17, 1922. Serial No. 537,340.

To all whom it may concern:

Be it known that I, ELMER G. FIPPENGER, a citizen of the United States, residing at Nekoosa, in the county of Wood and 5 State of Wisconsin, have invented certain new and useful Improvements in Blowers for Silos, of which the following is a specification.

The present invention relates to blowers 10 for silos and has for its principal object to provide an extensible discharge pipe therefor which is conveniently operated and which may be placed in a convenient position in relation to the table when not in 15 use.

With the above and numerous other objects in view as will appear as the description progresses, the invention resides in certain novel features of construction, and 20 the combination and arrangement of parts as will be hereinafter more fully described and claimed.

In the drawing:—

Figure 1 is a side elevation of the device 25 showing the discharge pipe in an operative position,

Figure 2 is a fragmentary side elevation showing the discharge pipe in an inoperative position,

30 Figure 3 is a transverse section on line 3—3 of Figure 2.

Figure 4 is a perspective view of one end of the table showing the blower casing,

Figure 5 is a fragmentary longitudinal section through the discharge pipe, and

Figure 6 is a horizontal section through the device, and

Figure 7 is a transverse section taken on the line 7—7 of Figure 5.

40 Referring to the drawing in detail it will be seen that 1 designates the usual table supported on the frame 2 mounted on the wheels 3. This table may be of any preferred or conventional construction and has mounted at one end thereof a bracket 4 to which is attached the blower casing. The blower casing is formed in two sections which are separable from each other. One of the sections 5 is rigidly attached to the bracket 4 and has a tube 6 leading therefrom to the upper side of the table 1. A pair of arm brackets 7 extend from the table above and beyond the section 5 and terminate in trunnion receiving portions 8 which receive the trunnions 9 carried by the collar 10 which supports the discharge

pipe. This discharge pipe is formed from a plurality of telescopically associated sections. The lower or main section 11 is mounted on the blower casing section 12 60 and the collar 10 is also mounted on the main section 11 in such a manner that when the discharge pipe is rotated on the trunnions 9 the section 12 will engage the section 5 so as to form a complete blower. In 65 the present illustration, I have shown three sections of the deflector but it is of course understood that there may be any desired number and that the present illustration is merely given by way of example. The intermediate section 13 is flared at its bottom end as at 14 and is movable within the section 11. The top section 15 is also flared at its bottom end at 14 and its upper end is provided with a curved deflector 16. The 70 sections 11 and 12 have journalled therein adjacent their upper ends the pulleys 17. A collar 18 is provided adjacent the bottom end of the section 15 and a plurality of cables 19 are attached thereto 80 at one end and are trained over the pulleys 17 in the section 13 and are connected to a collar 20 at the upper end of the section 11 so that when the section 13 is raised the section 15 will be extended in respect to 85 the section 13. Of course, this system may be carried out indefinitely. The main or bottom section 11 has cables 22 trained over its pulleys 17 and the ends thereof are attached to a suitable collar provided at the 90 bottom of the section 13. The other ends of these cables 22 are trained about a plurality of drums 25 which are keyed to shafts 26 that are journalled in the bracket arms 27 at one end and in the section 11 at the 95 other ends or rather in a suitable collar provided for this purpose. It will be noticed that each of the drums 25 is provided with a beveled gear 28 and that the beveled gears mesh with each other so that upon rotation of one of the drums all of the drums will be operated in unison. One of the drums is provided with a crank 29 for rotation thereof. It will therefore readily be seen by an inspection of the drawing 100 that when the cables 22 are wound about the drums 25 that the discharge pipe will be extended and vice versa. When the discharge pipe is not in use it may be rotated downwardly so as to extend parallel with the table 1 and a suitable hook 30 is engageable with the eye 31 so as to hold the 105 110

parts in the position as shown in Figure 2. This feature of the device is controlled by the cable 33 wound about the drum 34 carried by the frame 2 and fixed at one end to the movable case section 12. For convenience I have designated the discharge pipe by the letter D and fan blower casing by the letter B. This fan casing has suitable fastening devices 36 so as to hold the parts in closed position and these fastening devices are preferably of a resilient nature. Any suitable fan 38 is carried within the casing B and no detailed description thereof is necessary. This fan may be driven by a belt (not shown) trained over the pulley 39.

Having thus described my invention what I claim as new is:—

1. In combination, a fan casing comprising a pair of sections, a support, one of said sections fixed to said support, a discharge pipe, the other of said sections fixed to said

discharge pipe, and means whereby said discharge pipe may be rotatably mounted on said support in the manner and for the purpose specified.

2. In combination, a fan casing, comprising a pair of sections, a support, one of said sections fixed to said support, a discharge pipe, the other of said sections fixed to said discharge pipe, a bracket extending from said support, said discharge pipe fulcrumed on said bracket whereby it may be rotated for placing together or separating the sections of the fan cases, and means for rotating the discharge pipe to an operative position.

In testimony whereof I affix my signature in presence of two witnesses.

ELMER G. FIPPENGER.
